Primary Examiner — Clare E Heflin(74) *Attorney, Agent, or Firm* — Raymond Sun(57) **CLAIM**

The ornamental design for a lighting apparatus, as shown and described.

DESCRIPTION

FIG. 1 is a perspective view of a lighting apparatus showing my new design.

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view of the lighting apparatus.

The broken lines shown in FIG. 3 depict portions of the lighting apparatus that form no part of the claimed design.
